Des. 234,829
Patented Apr. 8, 1975

234,829

DRAWER-EQUIPPED TRAVELING BAG OR THE LIKE

Edna H. Edwards, 1100 Chantilly Road,
Los Angeles, Calif. 90024

Filed Oct. 6, 1972, Ser. No. 295,592

Term of patent 14 years

Int. Cl. D3—01

U.S. Cl. D87—5 G

FIG. 1.

FIG. 2.

FIG. 4.

FIG. 3.

FIG. 1 is an upper front perspective view of a drawer-equipped traveling bag showing my new design, the bag and access flap being shown in closed condition;

FIG. 2 is a fragmentary perspective view thereof, with the access flap shown in its open position and the drawer in its closed position;

FIG. 3 is a fragmentary perspective view thereof similar to FIG. 2, with the drawer shown in its opened position; and

FIG. 4 is a lower rear perspective view thereof.

I claim:

The ornamental design for a drawer-equipped traveling bag or the like, substantially as shown.
